CLAIM

The ornamental design for a grill brush handle, as shown and described.

DESCRIPTION

FIG. 1 is a top perspective view of a grill brush handle showing our new design;

FIG. 2 is a front elevational view thereof;

FIG. 3 is a rear elevational view;

FIG. 4 is a left side elevational view thereof, the right side being a mirror image;

FIG. 5 is a top plan view thereof; and,

FIG. 6 is a bottom plan view thereof.

The broken lines shown in FIGS. 1-6 are for illustrative purposes only and form no part of our claimed design.
